UNITED STATES PATENT OFFICE.

DAVID M. MOTHERWELL, OF CHICAGO, ILLINOIS, ASSIGNOR TO THE WHITMAN & BARNES MANUFACTURING COMPANY, OF AKRON, OHIO.

DESIGN FOR A CULTIVATOR-TOOL FRAME.

SPECIFICATION forming part of Design No. 29,070, dated July 19, 1898.

Application filed September 22, 1897. Serial No. 652,658. Term of patent 14 years.

To all whom it may concern:

Be it known that I, DAVID M. MOTHERWELL, a citizen of the United States, residing at Chicago, in the county of Cook and State 5 of Illinois, have by my own industry, genius, efforts, and expense invented and produced a new, useful, and original Design for a Cultivator-Frame, of which the following is a specification, reference being had to the accompanying drawings.

Figure 1 is a perspective view, Fig. 2 a plan view, and Fig. 3 a side elevation, of the cultivator-frame embodying my new design.

The leading or material features of my design consist, essentially, of the cruciform frame having the two lateral arms 1 and 2 and the central rear arm. They also consist in the configuration of the lateral arms or wings, the configuration of the central arm and the 10 lugs or projections therein, and the configuration of the tool-sockets. These lateral arms or wings 1 and 2, of the form substantially as shown in the drawings, contain tool-sockets 4, 5, 6, and 7 and have a skeleton 15 structure which gives them a light but substantial appearance, 15, 16, 17, 18, 19, and 20 representing open spaces therein. The cen-

tral arm of the frame, having the form substantially as shown, contains the tool-socket and bears upon its upper face the lugs 11, 12, 30 and 13, an open space, represented by 14, being left between its lateral walls. The tool-sockets are composed, substantially, of arcs 9, having the angle 10 opposite thereto.

Having thus described my invention, what 35 I claim as new, and desire to secure by Letters Patent, is—

1. The design for the lateral arm of a cultivator-frame, substantially as shown and described.

2. The design for the central arm of a cultivator-frame having lugs arranged and disposed along said arm, substantially as shown and described.

3. The design for a tool-socket of a cultivator-frame, substantially as shown and described.

4. The design for a cultivator-frame as herein shown and described.

DAVID M. MOTHERWELL.
